UNITED STATES PATENT OFFICE.

CHARLES B. SANDERS, OF MONTCLAIR, NEW JERSEY, ASSIGNOR TO THE UNION BAG & PAPER COMPANY, OF NEW YORK, N. Y., A CORPORATION OF NEW JERSEY.

BAG-MACHINE.

1,249,509.

Specification of Letters Patent. Patented Dec. 11, 1917.

Application filed July 28, 1916. Serial No. 111,758.

To all whom it may concern:

Be it known that I, CHARLES B. SANDERS, a citizen of the United States, residing at Montclair, New Jersey, have invented certain new and useful Improvements in Bag-Machines, of which the following is a clear, full, and exact description.

This invention relates to bag machines and improvements upon such machines as those shown and described in the Stilwell Patent #417,346, dated December 17, 1889. One object of the present invention is to provide mechanism for making paper bags of the type which have bellows sides and a square bottom connected by folds with said sides in such a way that the bag may be opened up like a box, with a side seam, that is to say, a seam at one edge of the flat face of the bag.

Another object of the invention is to provide means for producing slits at intervals in the traveling web of paper folded over the former plates, in such a way that portions of the web are protected or guarded against the slitting action.

Other objects are to provide improved draw rolls specially located in machines of the class mentioned for pasting down and forming the longitudinal seam of the bag, and to improve bag machinery of the said class generally so as to render it more efficient and satisfactory.

These being among the objects of the present invention, the same consists of certain features of construction and combinations of parts to be hereinafter described and then claimed with reference to the accompanying drawings illustrating a desirable embodiment of the invention, and in which—

Figure 1 is a plan of a portion of the mechanism for forming a bellows folded tube and severing it into bag blanks;

Fig. 2 is a side elevation of the same mechanism;

Fig. 3 is a side elevation of the ingoing end of the machine, showing the paste-applying means and other adjacent parts;

Fig. 4 is a plan of the parts shown in Fig. 3;

Fig. 5 is a section on the line 5—5 Fig. 2, the parts being enlarged, to show the means for guiding one portion of the folded tube against cutting when another portion is being slit;

Fig. 6 is a detail plan view of the guard;

Fig. 7 is an enlarged detail view of the improved draw rolls;

Fig. 8 is a plan view of a bag blank folded out to show just where the slits are made in the bag bottom; and

Fig. 9 is a perspective view showing the said blank folded over and just before the seam is produced in the bag.

Referring to the drawings, the frame 10 supports a roll of paper 11 and a paste-holder or receptacle 12, together with guide rollers 13, 14, adjacent the paste-holder. Former plates 15, 16 are supported from the frame in any suitable manner, while guide fingers 17 are located near the receiving end of the former plates, as shown more clearly in Figs. 3 and 4. Guide rollers or disks 18, 19 are also provided, the edges of which work between the said former plates. Except for the location of the paste-holder or receptacle, at the other end of the paper roll 11, all of said parts may be constructed and arranged as in aforesaid patent. Clips 20, 21 are also provided to form guides for the folded web of paper, substantially as in said patent, except that the position of the said clips is reversed. The function of the said parts is substantially the same as in said patent, but the web of paper is conducted to the former plates in such a way that the seam to be formed does not run along the middle of the upper plate but along one side thereof, or at that side which corresponds with the other end of the paper roll from that at which the paste-holder is located.

Slitter knives 22, 23 are mounted on rotary shafts 24, 25 driven as by gears 26, 27, for the purpose of slitting the folded web of paper longitudinally. Located between the upper former plate 15 and one of the slitters 22, as shown in Fig. 5, is a guard device 28. As shown in said figure and in Fig. 6, said guard is provided with a base portion or flange 29 and a table or rest portion 30 which is raised somewhat above the base portion 29 and is connected with it by a web 31. The said guard 28 is positioned transversely of the upper former plate 15, and its base portion is secured thereto by means of suitable fastenings 32, while the table or rest portion 30 extends transversely of the former plate 15, or in a direction away from the middle of said plate. A slot 33 extends transversely of the end of the table or rest

portion 30 and opens out at one edge of the same, said slot being so positioned as to register with the adjacent rotating slitter 22.

The machine is furthermore provided with improved draw rolls. The draw roll 34 may be of the ordinary type as in said patent, while the draw roll 35 is of a special type, both of said rolls being mounted upon their shafts 36, 37, which are provided with intermeshed gears 38, 39 whereby the upper shaft may be driven from the lower shaft. The lower draw roll is fixed upon the shaft 36, while the draw roll 35 is positively driven in the usual way for coöperating with the roll 34 to draw the folded blank or tube along the lower former plate 16. Draw roll 35 may be composed of two sections secured as by set screws 40 to the shaft 37, the ends of said screws entering a channel in the said shaft so that said sections may be adjusted. The outer end of the draw roll 35 is reduced or recessed so as to receive a preferably hard steel ring or collar 41, which is driven onto said reduced portion so as to be firmly held thereon. The position of the ring or collar 41 is such that it is in alinement with the slitter 22 which coöperates with the guard 30. That is to say, inasmuch as the bags to be made on this machine are made with a seam located at one edge, the said ring or collar 41 is positioned so as to press the pasted edge of the folded tube onto the unpasted edge, said edges being pressed together by the said ring and the lower draw roll so as to produce the edge seam. In order to properly operate in producing the edge seam, the ring or collar 41 is provided with one or more annular presser portions which adjoin an annular groove or grooves. Two grooves 42, 43 are shown, an annular presser portion 44 being located to the side of one groove, and an annular presser portion 45 being located between said grooves. The function of the annular presser portions is to press upon the pasted edge of the tube so as to press it against the unpasted edge, which results in squeezing the paste laterally, means for the lateral movement or escape of the paste being provided by the annular grooves 42, 43. The joint of the seam will be pasted along two lines represented by the grooves 42, 43, as much of the paste is squeezed out from under the presser portions 44, 45.

A bag blank is shown in Figs. 8 and 9. A folded web 46 is provided with intermediate face 47 and an opposite face 48, said faces being comparatively wide and intended to form the front and back of the bag ultimately produced. A bellows fold is shown between the faces 47, 48, and another bellows fold between the face 47 and the edge 49, which edge during the passage 65 of the folded web through the machine is

folded over onto the edge of the upper former plate. The face 48 of the blank receives the paste from the paste-holder which is located at one end of the paper roll, and said face is folded over upon the upper former plate in a manner similar to that in the aforesaid patent. The paste, however, is applied to the edge 50 of said face 48 instead of to the other edge of the web, as is done in said patent. Before the pasted edge is pressed onto the unpasted edge 49 by the action of the draw rolls, the slitters 22, 23 slit the tube or folded-over web, at two points, top and bottom. The folded-over edge 49 of the web or tube passes along the upper former plate between it and the guard 30, while the pasted edge 50 is guided over the said guard, as shown in Fig. 5. It will be seen that the edge 50 will be slit by the adjacent slitter 22 without the folded-over edge 49 being also slit. This might happen if a guard such as 30 were not provided. After the folded web or blank passes the slitters, it goes to the draw rolls where the edge 50 is pasted down upon the edge 49, whereby an edge seam for the bag blank is provided. The so-formed bag passes to the serrated edge of the lower former plate, and the bag blanks are there severed in the well known manner, the severance taking place at the slits 51, 52 which have been formed in the folded-over tube or blank. From this point the bag blank passes along to the bottom-forming mechanism, which forms no part of this invention, as suitable mechanism is fully shown in the aforesaid patent.

It is obvious that the invention is susceptible of modification, as parts may be omitted, parts added and parts substituted without departing from the spirit and scope of the invention as claimed.

What I claim as new is:—

1. In a bag machine, the combination of a frame, former plate supported thereon, a paste-holder supported in advance of said plates toward one end of the roll of paper, means for conducting a web over said plates after applying paste from said holder to the edge portion of said web which is adjacent said holder and for forming the tube over said plates, draw rolls having spaced presser portions adjacent the edge of one of said plates but just inside the line of said plate-edge, and in advance of the rear end of said plate, for pasting said edge portion upon the other edge portion of said web, whereby a tube with a side seam is formed.

2. In a bag machine, the combination of former plates over which a web may be longitudinally folded so that its edge portions may overlap, means for drawing said folded web along over said plates, a slitter for longitudinally slitting the portion of said web which is more remote from one of

- said plates than the other portions of said web, and a guard over and under which the said edge portions respectively travel, for holding raised one edge portion and protecting the other edge portion of said web which is nearer to said plate against the action of said slitter, said slitter having a path of movement out of the plane of said edge portion nearer said plate.
- 10 3. In a bag machine, the combination of former plates over which a web may be longitudinally folded, means for drawing said web along said plates, a slitter for

longitudinally slitting an edge portion of said web at intervals, and a guard fixed to 15 one of said plates and raised above it at one end for protecting the other edge portion of said web against said slitter, the said edge portions being caused to travel at opposite sides of said end of said guard.

Signed at Hudson Falls, N. Y., this 25th day of July, 1916.
